NEUTRALIZED CATHODE-RAY DEFLECTION TUBE

Paul J. Selgin, Fort Wayne, Ind., assignor, by
mesne assignments, to Farnsworth Research
Corporation, a corporation of Indiana

Application January 20, 1947, Serial No. 723,035

12 Claims. (Cl. 250—27)

1

This invention relates to cathode ray tubes and particularly to devices of this character which are capable of operating substantially independently of the influence of stray fields.

There are many cases in which it is desirable to use cathode ray tubes for the purpose of signal generation and/or signal modulation. Devices capable of such uses, in general, comprise a cathode ray tube wherein one or more electron beams are deflected over a target electrode of particular configuration under the control of intelligence signals. Heretofore, such devices have been particularly susceptible to the influence of stray fields. As a result, the signals developed in the output circuit have contained spurious effects caused by the stray fields.

It has been proposed to employ an even number of electron beams, each of which is deflected over an associated target electrode structure in order to overcome the deleterious effects of stray fields. Half of the beams have been deflected in one direction and the other half of the beams have been deflected in the other direction, all under the control of the signals. In this manner, the undesired deflections of the beams caused by the stray fields have effectively been cancelled.

However, such structures are relatively cumbersome for the reason that generally they require the use of separate apparatus for forming and deflecting the respective beams over the target electrodes. Not only is such apparatus relatively costly to produce, but also it is difficult to operate. Facilities must be provided for properly orienting each of the electron beams relative to its associated deflecting and target electrodes.

It, therefore, is an object of the present invention to provide a cathode ray tube structure, wherein initially a single electron beam is utilized to produce a plurality of beams for deflection, together with a relatively simple deflecting and target electrode system, whereby to effectively neutralize the effect of stray fields upon the electron beam deflections.

In accordance with this invention, there is provided a cathode ray tube having means for forming an electron beam and directing it toward a target electrode structure. Additionally, the tube is provided with facilities cooperating with a deflecting system, whereby the electron beam is effectively divided into two parts. The deflecting system is operated in such manner that, under the control of intelligence signals, the two portions of the electron beam are deflected in opposite directions. A target electrode structure is provided and has a form suitable to collect sub-

2

stantially all of the electrons in the two beam portions so that, by connecting the target electrode structure to an output circuit, there are developed signal effects representing only the electron beam deflections which are directly produced under the control of the signals. All beam deflections caused by the effects of stray magnetic or electrostatic fields are effectively cancelled in the output circuit. Additionally, the tube may be provided with a metallic shield located so as to surround the space between the deflecting system and the target electrode structure. Such a shield provides additional shielding of the electron beam portions from stray electrostatic fields. More importantly, however, the shield provides a substantially field-free space between the deflecting system and the target electrode structure.

For a better understanding of the invention, together with other and further objects thereof, reference is made to the following description, taken in connection with the accompanying drawing, and its scope will be pointed out in the appended claims.

In the accompanying drawing:

25 Fig. 1 is a diagrammatic representation of a cathode ray tube having an electrode structure which embodies the invention in an illustrative form, and

30 Figs. 2, 3 and 4 are illustrations of typical relationships between the electron beam portions and the target electrode structure which are produced under the control of the signals.

Having reference now to Fig. 1 of the drawing, the cathode ray tube is provided with an evacuated envelope 10. At the left hand end of the tube envelope there is provided an electron gun for developing an electron beam and projecting it generally toward the right hand end of the tube. The electron gun includes a cathode 11 which may be entirely conventional and which is capable of emitting copious quantities of electrons when energized in any suitable manner, such as by heating either directly or indirectly. In back of the cathode there is provided a repelling electrode 12. In front of the cathode there is provided an accelerating anode electrode 13 which has formed therein a centrally located aperture 14 in substantial alignment with the cathode. Preferably, the aperture 14 is provided with a screen or grid structure 15, whereby to effectively nullify the lens effect which the aperture otherwise would have, and at the same time, to permit the passage of the electrons through the aperture. In the illustrated form of electron gun, the accelerating anode electrode 13 has the

general form of an hyperbola and the repelling electrode 12 is formed in such a manner that the sides thereof are the asymptotes of the hyperbolic anode. In such a case the cathode 11 is located at the focal point of the hyperbola.

In front of the anode 13 there is located an electrode 16 which may be operated as illustrated at the same potential as the accelerating anode. This electrode is located substantially at the center of the electron beam 17 issuing from the anode aperture 14. Its purpose is to divide the beam 17 into two substantially equal portions, 17a and 17b. It also functions in manner to be described to prevent electrons from striking one of the electrodes of the deflecting system.

In front of the beam separating electrode 16, there is provided a deflecting system which, in its illustrated form, comprises three substantially parallel plates 18, 19 and 20. The plates 18 and 20 constitute an external deflecting electrode structure which has a configuration suitable to form an aperture located in the paths of the electron beam portions 17a and 17b. The plate 19 constitutes an internal deflecting electrode structure which is located in the aperture of the external deflecting electrode structure substantially midway between the two beam portions.

The deflecting plate 19 thus is located in substantial alignment with the beam separating electrode 16. Consequently, any electrons of the beam 17 which otherwise might strike the deflecting plate 19 are intercepted by the electrode 16. Therefore, the center deflecting plate 19 is not subject to potential variations as a result of electron impingement thereof.

Behind the deflecting system there is located a substantially cylindrical hollow metallic electrode 21. This electrode is open at both ends and extends longitudinally of the tube along the central axes of the electron beam portions 17a and 17b. In some cases if desired, the shielding electrode 21 may be in the form of a metallic wall coating placed on the inside surface of the envelope 10. However, in the form disclosed, the shielding electrode may be employed advantageously for mounting some of the other electrodes of the tube in a manner to be described.

A target electrode system is provided adjacent the other end of the shield 21 and, as shown, may include a pair of flat plates 22 and 23 located in substantial alignment at right angles to the electron beam portions. These electrodes do not extend completely to the center of the tube, but instead provide a centrally located space through which all or a part of the electron beam portions may pass. Additionally, there is provided a flat baffle plate electrode 24 in the space between the target electrodes 22 and 23 and which extends longitudinally of the tube substantially as shown. Finally, the target electrode system includes a flat plate electrode 25 located in alignment with the space between the electrodes 22 and 23 substantially at right angles to the paths of the electron beams. The plates 22 and 23 constitute an electron intercepting electrode structure which has a configuration to form an aperture centrally located relative to the undeflected paths of the beams. The plate 25 constitutes an electron collecting electrode structure located behind the interceptor aperture.

The various electrodes of the cathode ray tube, in accordance with this invention, as described, are energized by connections to suitable sources of signals, power, etc. The power source for the tube electrodes is represented as a battery 26, the

voltage of which is distributed to the tube electrodes in a suitable manner by means of a voltage divider 27 connected across the terminals of the battery. The electron repelling electrode 12 is connected to the most negative terminal of the power supply system. The cathode 11 is operated by a suitable connection to the voltage divider at a point of somewhat more positive potential. The accelerating anode 13 and the electron beam separating electrode 16 are connected to the most positive point of the voltage supply system as shown. The upper and lower deflecting plates 18 and 20 respectively, the shielding electrode 21, the target interceptor electrodes 22 and 23 and the baffle electrode 24 are all connected to a somewhat more positive point on the voltage divider than that to which the cathode 11 is connected.

A signal source 28 is connected to the center 20 deflecting plate 19 and to a slightly more positive point on the voltage divider 27 than that to which the deflecting plates 18 and 20 are connected. This voltage divider point also is grounded. The target collector electrode 25 is connected through 25 an output or load resistor 29 to the positive terminal of the voltage supply system. Finally there is provided a utilization circuit 31 connected across the resistor 29.

Referring now to the operation of the cathode 30 ray tube embodying this invention, the electron gun structure produces a single electron beam 17, which as described, is separated by the electrode 16 into two substantially equal portions 17a and 17b. In operating the device, the outer deflecting 35 plates 18 and 20 are maintained at a substantially constant potential, while the center plate 19 is operated at a potential which is varied in accordance with the signals impressed thereon from the source 28. Consequently, the upper portion 17a of the electron beam which passes between the deflecting plates 18 and 19 and the lower portion 17b of the beam which passes between the deflecting plates 19 and 20 are oppositely influenced by the varying potential of the center plate. Deflections of these two beam portions therefore are in opposite directions. The target electrode structure is so arranged relative to the two electron beam portions that each of the beam portions at all times impinges both on the collector electrode 25 and on one of the interceptor electrodes 22 or 23. As these beam portions are deflected under control of the signals, the electron impingement of the interceptor and collector electrodes varies.

A better understanding of the behavior of the 55 two beam portions in their relation to the target electrode structure may be had by reference to Figs. 2, 3 and 4. Fig. 2 illustrates the case where the signal voltage which is impressed upon the deflecting system is zero. In this case there are substantially no deflections of the electron beam portions. Approximately half of the upper beam portion 17a impinges upon the upper interceptor electrode 22 and the other half impinges upon the collector electrode 25. Similarly, the lower beam portion 17b impinges in substantially equal magnitudes upon the lower interceptor electrode 23 and the collector electrode 25.

The signal which is developed in the output 70 circuit resistor 29 is dependent upon the electron collection by the electrode 25. Since approximately half of the electrons of each of the two beam portions is collected by this electrode, there is developed in the resistor 29 a voltage representative of this relationship between the elec-

tron beam portions and the target electrode structure.

Assume now that a signal of positive polarity is impressed upon the center deflecting electrode 19. The upper beam portion 17a thereby is deflected downwardly and the lower beam portion 17b is deflected upwardly. Fig. 3 illustrates the relation of these beam deflections to the target electrode structure. Both beam portions are deflected toward the central longitudinal axis of the tube. In this case the major parts of both beam portions impinge upon the center collecting electrode 25 and only relatively small parts of the beam portions impinge upon the interceptor electrodes 22 and 23, respectively. As a consequence a greater number of electrons are collected by the electrode 25 than in the case where the beam deflections are effected by a zero signal voltage. The upper terminal of the output resistor 29 as a result develops a more negative potential. Since the lower terminal of this resistor is connected to a point of substantially constant potential, a negative voltage relative to the voltage representing a zero signal is developed in the output resistor for impression upon the utilization circuit 31.

If now a signal of negative polarity is impressed upon the center deflecting electrode 19, the upper beam portion 17a is deflected upwardly and the lower beam portion 17b is deflected downwardly. This condition is illustrated in Fig. 4. It is seen that the greater part of the beam portion 17a impinges upon the upper interceptor electrode 22 and only a small part impinges upon the collector electrode 25. Similarly the greater portion of the lower beam portion 17b impinges upon the lower interceptor electrode 23, while only a small part of this beam portion impinges upon the collector electrode. Consequently, in this case the electron collection by the electrode 25 is less than in the case of a zero signal. As a result the upper terminal of the output resistor 29 becomes less negative, whereby to develop a positive output voltage in relation to the zero signal output voltage for impression upon the utilization circuit 31.

Suppose that, externally of the tube, there exists a stray field of such a character that the electron beams tend to be deflected upwardly. Such a field will effect substantially the same magnitude of deflection of both beam portions. Considering first the upper beam portion 17a, it is seen that more electrons will be collected by the upper interceptor electrode 22 and less electrons by the center collecting electrode 25 than would occur if the beams were not subjected to the stray field. On the other hand, the upward deflection of the other beam portion 17b by the external field causes more electrons to be collected by the center collector electrode 25 and less electrons by the lower interceptor electrode 23. The result is that the loss of electrons from the upper beam portion 17a by the center electrode 25 is offset by the gain of electrons by this electrode from the lower beam portion 17b. Consequently, the signal voltage developed in the resistor 29 is the same as it would be if no stray field were present.

It should be apparent that a device such as that described embodying the invention has several advantages over prior art cathode ray tubes of the deflecting modulation type. In the first place, a single electron gun structure may be employed, with the attendant advantages of simplifying tube construction and power consump-

tion. Also, the deflecting electrode structure wherein two deflecting systems are provided by the use of three electrodes has the advantage of relative simplicity of construction. The arrangement of such a deflecting system enables the simultaneous deflections of two beam portions in opposite directions. Such a facility enables the device to operate substantially independently of stray fields.

10 The tube, being provided with a shielding electrode 21, also is advantageous for the reason that it simplifies the construction of the device. A great many of the electrodes located at either end of the shield are electrically connected thereto and at the same time may advantageously be mechanically attached to the shielding electrode. Furthermore, others of the electrodes which may be operated at different potentials from the shield may also be supported mechanically thereby through the use of suitable insulating supports. Furthermore, the shield serves to provide additional protection for the electron beam from any external electrostatic stray fields. More importantly however, it provides a field-free space through which the electron beam may pass in the major portion of its travel from the deflecting electrode system to the target electrode structure. In this manner, as is well known in the art, the electrons maintain the directions imparted to them by the deflecting system.

30 It is also advantageous to employ the barrier electrode 24 in the aperture formed between the upper and lower interceptor electrodes 22 and 23 respectively. By maintaining the barrier electrode at a potential which is no higher than that of the two adjacent electrodes, it serves to inhibit the emission of secondary electrons by the adjacent electrodes. In some cases it may be more desirable to impress a potential upon the electrode 24 which is somewhat negative relative to the electrodes 22 and 23. Inasmuch as the electron beam portions strike the target electrodes with considerable velocity, there is a tendency to liberate secondary electrons from these electrodes. The presence of the barrier electrode 24 however, produces a field condition which overcomes this tendency for the liberation of secondary electrons. As is well known in the art, where utilization is not made of secondary electrons, it is necessary to provide facilities for collecting them in order to avoid the introduction of spurious signal effects in the signal representative voltages developed in the output circuit. It therefore is more convenient to inhibit the liberation of such secondary electrons than it is to permit them to be liberated and then to collect them.

40 However, a device in accordance with the present invention may have incorporated therein an electron multiplier for functioning in conjunction with the target electrode structure. In such a case direct employment may be made of secondary electrons liberated by the impingement of the electron beam portions upon the target electrode structure. A barrier electrode, such as 24, would not be used in such an event. As many stages of electron multiplication as desired may be employed in any manner well known in the art.

50 70 It also is considered to be within the scope of the present invention to couple the electrode structure of a tube embodying the invention to an output circuit in any well known manner other than that disclosed specifically herein for illustrative purposes. For example, it is obvious that

the electron impingement of the interceptor electrodes 22 and 23 also varies in accordance with the deflections of the beam portions under the control of the signals. Consequently, the interceptor electrodes may be coupled to an output circuit resistor, such as the resistor 29, instead of the collector electrode 25. In such a case however, the polarity of the voltages developed in the output circuit resistor would be reversed from those described, since the electron impingement of the interceptor electrodes is of opposite phase to the electron impingement of the collector electrode.

While there has been described what at present is considered the preferred embodiment of the invention, it will be obvious to those skilled in the art that various changes and modifications may be made therein without departing from the invention, and, therefore, it is aimed in the appended claims to cover all such changes and modifications as fall within the true spirit and scope of the invention.

What is claimed is:

1. A cathode ray tube comprising, means for developing two electron beam portions and for projecting said beam portions toward a target electrode system, an electron beam deflecting system located adjacent to said beam developing means and comprising an external electrode structure and an internal electrode structure, said external deflecting electrode structure having a configuration to form an aperture located in the paths of said beams, said internal deflecting electrode structure being located substantially coaxially with said beam paths in the aperture of said external electrode structure, said deflecting electrode system functioning in response to varying potentials of opposite polarity on said internal and external electrode structures respectively to concurrently deflect both of said two beam portions in opposite directions, and a target electrode system located remote from said deflecting electrode system and including an electron interceptor electrode structure and an electron collecting electrode, said interceptor electrode structure being arranged to form an aperture centrally located relative to the undeflected paths of said two beam portions and said electron collector being located behind said interceptor aperture, whereby the deflections of said two electron beam portions oppositely vary the electron impingement upon said interceptor and said collector electrodes respectively.

2. A cathode ray tube comprising, means for developing two electron beam portions and for projecting said beam portions toward a target electrode system, an electron beam deflecting system located adjacent to said beam developing means and comprising three electrodes, two of said deflecting electrodes being mounted on opposite sides of the paths of said beam portions and each being maintained at a substantially constant potential and the third one of said deflecting electrodes being located substantially coaxially with said beam path and subject to a varying potential of opposite polarity to the potential of said two deflecting electrodes, said deflecting electrode system functioning to divide said electron beam into two portions which, under the control of the varying potentials impressed upon said third deflecting electrode, are deflected concurrently in opposite directions, and a target electrode system located remote from said deflecting electrode system and including an electron interceptor electrode structure and an elec-

tron collecting electrode, said interceptor electrode structure having a form to define an aperture centrally located relative to the undeflected paths of said two beam portions and said electron collector being located behind said interceptor aperture, whereby the deflections of said two electron beam portions oppositely vary the electron impingement upon said interceptor and said collector electrodes respectively in accordance with the potential variations of said third deflecting electrode.

3. A cathode ray tube comprising, means for developing an electron beam and for projecting said beam toward a target electrode system, a target electrode system including an electron interceptor electrode structure and an electron collecting electrode mounted at right angles to the path of said beam, said electron interceptor electrode structure having a form to define an aperture symmetrically located relative to the center of said beam path, said electron collector being located behind said interceptor aperture, and an electron beam deflecting system located between said beam developing means and said target electrode system and comprising three electrodes mounted in mutually spaced relationship, the center one of said deflecting electrodes being located substantially coaxially with said beam path and the outer deflecting electrodes being located on opposite sides of said beam path, a voltage variation between said center deflecting electrode and said outer deflecting electrodes causing said beam to converge and diverge, whereby to oppositely vary the electron impingement upon said interceptor and said collector electrodes respectively.

4. A cathode ray tube comprising, means for developing an electron beam and for projecting said beam toward a target electrode system, a target electrode system including three electrodes mounted at right angles to the path of said beam, two of said electrodes constituting an electron interceptor being spaced apart symmetrically relative to the center of said beam path and the third electrode constituting an electron collector being located behind said interceptor electrodes in alignment with the space therebetween, and an electron beam deflecting system located between said beam developing means and said target electrode system and comprising three plates mounted in spaced planes parallel to the path of said beam, the center one of said deflecting plates being mounted substantially coaxially with said beam path and the outer deflecting plates being mounted on opposite sides of said beam path, a voltage variation between said center deflecting plate and said outer deflecting plates causing said beam to converge and diverge, whereby to oppositely vary the electron impingement upon said interceptor and said collector electrodes respectively.

5. A cathode ray tube comprising, means for developing an electron beam and for projecting said beam toward a target electrode system, a target electrode system including three plates mounted at right angles to the path of said beam, two of said plates constituting an electron interceptor being spaced apart symmetrically relative to the center of said beam path and the third plate constituting an electron collector being located behind said interceptor plates in alignment with the space therebetween, an electrode located in the space between said interceptor plates for inhibiting secondary electron emission by said interceptor plates, and an electron beam deflect-

ing system located between said beam developing means and said target electrode system and comprising three plates mounted in equally spaced planes parallel to the path of said beam, the center one of said deflecting plates being mounted substantially coaxially with said beam path and the outer deflecting plates being electrically interconnected and mounted on opposite sides of said beam path, a voltage variation between said center deflecting plate and said outer deflecting plates causing said beam to converge and diverge, whereby to oppositely vary the electron impingement upon said interceptor and said collector plates respectively.

6. A cathode ray tube comprising, means for developing an electron beam and for projecting said beam toward a target electrode system, a target electrode system including three substantially flat plates mounted at right angles to the path of said beam, two of said plates constituting an electron interceptor being spaced apart symmetrically relative to the center of said beam path and the third plate constituting an electron collector being located behind said interceptor plates in alignment with the space therebetween, an electrode located in the space between said interceptor plates for inhibiting secondary electron emission by said interceptor plates, an electron beam deflecting system located between said beam developing means and said target electrode system and comprising three substantially flat plates mounted in equally spaced planes parallel to the path of said beam, the center one of said deflecting plates being mounted substantially coaxially with said beam path and the outer deflecting plates being electrically interconnected and mounted on opposite sides of said beam path, a voltage variation between said center deflecting plate and said outer deflecting plates causing said beam to converge and diverge, whereby to oppositely vary the electron impingement upon said interceptor and said collector plates respectively, and a hollow substantially cylindrical shield surrounding said electron beam between said deflecting and said target electrode systems.

7. A cathode ray tube comprising, an evacuated envelope, an electron gun located adjacent one end of said envelope for projecting an electron beam toward the opposite end of said envelope, means including an electrode located adjacent to said electron gun for dividing said beam into two portions, a deflecting structure for each of said beam portions including a plurality of parallel spaced plates, one of said plates being common to both deflecting structures, whereby said beam portions concurrently are deflected oppositely in response to a signal voltage impressed upon said deflecting structures, a pair of electron interceptor plates located partially in the respective paths of said beam portions adjacent the opposite end of said envelope, an electron collector electrode located partially in the paths of both of said beam portions, and an electrostatic shield surrounding the space between said deflecting structure and said interceptor electrodes.

8. A cathode ray tube comprising, an evacuated envelope, an electron gun located adjacent one end of said envelope for projecting an electron beam toward the opposite end of said envelope, an electrode located in said electron beam path adjacent to said electron gun for dividing said beam into two portions, a deflecting structure for each of said beam portions comprising three substantially parallel spaced plates, the center one of said

plates being common to both deflecting structures, whereby said beam portions concurrently are deflected oppositely in response to a signal voltage impressed symmetrically upon both deflecting structures, a pair of spaced electron interceptor plates located respectively in the paths of said beam portions adjacent the opposite end of said envelope, an electron collector electrode located in alignment with the space between said interceptor plates in the paths of both of said beam portions, and a metallic shield surrounding the space between said deflecting structure and said interceptor electrodes.

9. A cathode ray tube comprising, an evacuated envelope, an electron gun located adjacent one end of said envelope for projecting an electron beam toward the opposite end of said envelope, an electrode located at the center of said electron beam path adjacent to said electron gun for dividing said beam into two substantially equal portions, a deflecting structure for each of said beam portions comprising three substantially parallel spaced plates, the center one of said plates being common to both deflecting structures, whereby said beam portions concurrently are deflected oppositely in response to a signal voltage impressed upon said center plate, a pair of spaced electron interceptor plates located respectively in the paths of said beam portions adjacent the opposite end of said envelope, an electron collector electrode located behind the space between said interceptor plates in the paths of both of said beam portions, and a hollow metallic shield surrounding the space between said deflecting structure and said interceptor electrodes.

10. A signaling system comprising, a source of signals, a cathode ray tube having means including an electron gun for developing an electron beam divided into two portions, a deflecting electrode structure for each of said beam portions comprising a plurality of spaced electrodes located adjacent the respective paths of said electron beam portions, two of said deflecting electrodes being associated individually with said respective beam portions and a third one of said deflecting electrodes being associated with both of said beam portions, a target electrode structure located in the paths of said beam portions including a pair of electron interceptor electrodes and an electron collector electrode, said interceptor electrodes being located in the respective paths of said beam portions and said collector electrode being located in the paths of both of said beam portions, electrical connections between said two deflecting electrodes associated individually with the respective beam portions, means for coupling said signal source between said third deflecting electrode commonly associated with both of said beam portions and said 60 interconnected deflecting electrodes, an output circuit, and means for coupling said target electrode structure to said output circuit.

11. A signaling system comprising, a source of signals, a cathode ray tube having an electron gun for projecting an electron beam, means located adjacent said electron gun for dividing said beam into two portions, a deflecting electrode structure for each of said beam portions comprising a plurality of parallel spaced plates located adjacent the respective paths of said electron beam portions, a target electrode structure located in the paths of said beam portions and including a pair of spaced electron interceptor plates and an electron collector plate located in alignment with the space between said intercep-

tor plates, a metallic shielding electrode enveloping the space between said deflecting structure and said target electrode structure, electrical connections between the two outside ones of said deflecting plates, means for coupling said signal source between said center deflecting plate and said interconnected outside deflecting plates, an output circuit including a load impedance device, and means for coupling one of said target electrodes to said impedance device.

12. A signaling system comprising, a source of signals, a cathode ray tube having an electron gun for projecting an electron beam toward a target electrode structure, means located in the path of said beam adjacent said electron gun for dividing said beam into two portions, a deflecting electrode structure for each of said beam portions comprising three substantially parallel spaced plates located adjacent the respective paths of said electron beam portions, a target electrode structure including a pair of spaced electron interceptor plates and an electron collector plate located in back of said interceptor plates and in alignment with the space between said intercept-

10 tor plates, a hollow cylindrical metallic shielding electrode enveloping the space between said deflecting structure and said target electrode structure, electrical connections between said shielding electrode, said interceptor plates and the two outside ones of said deflecting plates, means for coupling said signal source between said center deflecting plate and said interconnected outside deflecting plates, an output circuit including a load impedance device, and means for coupling one of said target electrodes to said impedance device.
